SIDE SILL

Martin P. Blomberg, Chicago, Ill., assignor to
Pullman-Standard Car Manufacturing Company, a corporation of Delaware

Application July 16, 1934, Serial No. 735,359

8 Claims. (Cl. 105—418)

The primary object of this invention is to provide a side sill for railway cars which combines strength with lightness, and which is particularly suitable for use in light-weight cars of streamline form.

Further and other objects and advantages will become apparent as the disclosure proceeds and the description is read in conjunction with the accompanying drawings, in which

Fig. 1 is a diagrammatic, perspective view of the body framework of a railway car employing a side sill made in accordance with this invention;

Fig. 2 is a cross sectional view showing one form of side sill;

Fig. 3 is a cross sectional view showing another form of side sill;

Fig. 4 is a sectional view taken on the line 4—4 of Fig. 2;

Fig. 5 is a cross sectional view taken on the line 5—5 of Fig. 2;

Fig. 6 is a cross sectional view taken on the line 6—6 of Fig. 3;

Fig. 7 is a perspective view illustrating the manner in which the side sill is used to connect the side post with the transverse floor supports;

Fig. 8 is a view corresponding to Fig. 7 but illustrates the use of the side sill of Fig. 2;

Fig. 9 is a perspective view showing how the side sill of Fig. 2 frames into the end sill;

Fig. 10 is an enlarged detail perspective view showing the connection between the end sill and the side sill of Fig. 2; and

Figs. 11 and 12 are cross sectional views of the side sills of Figs. 2 and 3, respectively, (the views being taken looking in the opposite direction) showing the resemblance which the side sills bear to the lower case Greek alphabet letter lambda.

For the purpose of disclosure, two embodiments of the invention have been chosen for illustration and specific description, but the scope of the invention is not limited to these embodiments and the appended claims should be construed as broadly as the prior art will permit.

The recent trend toward increased speeds in railway transportation has resulted in the development of light-weight streamline trains, usually powered by internal combustion engines which drive generators for energizing electric traction motors carried on the car trucks. The streamline form of the cars has necessitated some changes in conventional car building practice, and one example of body framework which is suitable for cars of this type is shown in Fig. 1.

The main framework comprises a center sill

10, end sills 11 and 12 secured to opposite ends of the center sill, door end posts 13 and 14, and 15 and 16, rising from the end sills 11 and 12, respectively, anti-telescoping plates 17 and 18 supported by the door end posts, and top sills 19 and 20 connected by plates 21 and 22 to form a box girder which rests upon and is secured to the anti-telescoping plates 17 and 18 and the door end posts 13, 14, 15 and 16. Preferably this portion of the car framework is designed to carry 10 the major portion of the car load.

The shell of the car is formed by a plurality of ribs 23 which connect the top sills 19 and 20 with the upper part of the center sill 10. These ribs lie in vertical planes and are connected together by various longitudinal framing members, such as roof stringers 24, window header stringers 25, belt rails 26, side sills generally designated 27, and various floor stringers. The ribs when made in one piece, as shown in Figs. 1, 2 and 8 serve 20 as combined carlines, side posts and floor supports, but in some cases, it is desirable to form the side posts and floor supports in two pieces, as shown in Figs. 3, 6, and 7.

The belly of the car is formed by arcuate 25 J-bars 28 which connect the side sills to the bottom of the center sill. The J-bars are reinforced by struts 29 and 30.

Referring now to Fig. 2, the side sill 27 is in one piece and is preferably made of aluminum 30 or aluminum alloy formed by the extrusion process. The side sill has a relatively deep body portion 31 which furnishes sufficient resistance to vertical deflection and is provided with longitudinal insets 32 and 33 adjacent to the top 35 and bottom edges of the sill. These insets are adapted to receive outside sheathing plates 34 and 35 flush with the exterior face 36 of the side sill, as best shown in Fig. 2. The top portion of the side sill is further inset as shown at 37, so 40 that the rivets 38 which secure the ribs 23 to the side sill are covered by the outside sheathing plate 34 (see Fig. 2). The inside face 39 of the top inset is slightly concave to conform to the curvature of the rib 23. Rivets 40 secure the sheathing 45 plate 34 to the extreme upper edge of the side sill, and rivets 41 do likewise, but include also the ribs 23, see Fig. 4.

The arcuate J-bars 28 which form the belly of the car are secured to the lower edge of the 50 side sill by rivets 42 which also serve to secure the belly sheathing 35 in place.

Integrally formed with the body portion 31 is an inwardly extending flange 43 terminating in a downwardly inclined flange 44 which supports 55

the rib 23 and provides a suitable surface for riveting, the rivets being indicated at 45. In addition, the flanges 43 and 44 serve to materially increase the stiffness of the side sill and particularly to resist bending caused by side impact against the car.

The side sills are connected to the end sills in a manner best shown in Fig. 10. The end sill casting has a lug 46 which fits into the recess formed by the shoulder 47 of the inset 37 and the flange 43, and rivets 48 secure the two members together.

The cross sectional shape of the side sills 27 in both embodiments of the invention, exemplified by Figs. 2 and 3, resembles the lower case Greek alphabet letter lambda, as best shown in Figs. 11 and 12 (the cross sections representing the side sill on the right hand side of the car when looking toward the end sill 12 in Fig. 1).

20 The side sill shown in Fig. 3 differs slightly from the one shown in Fig. 2 and is used when the ribs 33 are broken at the side sills for economy of manufacture.

As shown, the side sill comprises a body portion 50 and an inwardly extending inclined flange 51, the body portion being somewhat thicker and not as deep as the side sill shown in Fig. 2. As before, the side sill is in one piece and is preferably an extruded aluminum or aluminum alloy member.

When this form of side sill is used, the side post section 52 of the ribs 23, and the cross supports 53, are joined to the side sill and to each other by splice plates 54 and 55, the outside flanges 56 of the rib sections being cut away, as indicated at 57, 58 to accommodate the splice plates. The plates are provided with flanges 59 and 60, the former providing a suitable surface for riveting to the side sill with rivets 61, and the latter providing a bearing surface for the floor stringer 62 riveted to the splice plates at 63 and 64. Rivets 65 secure the side post sections 52 to the splice plates and rivets 66 secure the floor support sections 53 to the splice plates.

45 The body portion 50 of the side sill has longitudinal insets 67 and 68 to receive the sheathing plates 34 and 35 flush with the outside face of the side sill, rivets 69 and 70 securing the sheathing plates and the splice plates to the body portion of the side sill.

The side sills of Figs. 2 and 3 are both relatively simple to form, particularly when made of aluminum or aluminum alloy and extruded. The same, or similar forms, however, may be made by casting or rolling, and material other than aluminum may be used.

What I claim is:—

1. A one piece side sill having a cross sectional shape corresponding approximately to the lower case Greek alphabet letter lambda and comprising a rigid member having a flange extending inwardly and downwardly from the lower portion thereof, said sill being adapted to be connected to the side posts of a railway car, the upper portion being adapted to be connected to the side sheathing of said car and the lower portion being adapt-

ed to be connected to the sheathing extending beneath the car.

2. A one piece side sill having a relatively deep body portion and an inwardly extending flange arranged at an acute angle to said body portion adjacent the lower edge thereof, the upper edge of said body portion having an inset extending in the direction of said flange. 5

3. For use in a railway car including body framework and sheathing over the framework, a one 10 piece side sill formed by extrusion and comprising a relatively deep body portion, and an inwardly extending flange, said body portion having longitudinal insets along its top and bottom edge adapted to receive the outside sheathing of 15 the car flush with the outer face of the side sill.

4. For use in a railway car having side posts and transverse floor supports, a one piece side sill having a body portion adapted to be secured to the side posts, and an inwardly extending flange 20 adapted to support the transverse floor supports and act as a stiffener for resisting side impacts, the upper portion of said body portion having an apertured inset for receiving an attaching rivet.

5. For use in a railway car having side posts to 25 which outside sheathing is applied, and transverse floor supports, a one piece side sill having a body portion adapted to be secured to the side posts, and an inwardly extending flange adapted to support the transverse floor supports and act 30 as a stiffener for resisting side impacts, said body portion having longitudinal insets adapted to receive the outside sheathing flush with the exterior face of the side sill.

6. For use in a railway car having side posts, 35 transverse floor supports and curved belly forming bars, an extended one piece side sill having a rigid body portion, the top of which is adapted to be secured to the side posts and the bottom to the belly forming bars, and an inwardly extending 40 flange adapted to support the transverse floor supports and act as a stiffener for resisting side impacts.

7. In a car body having side posts, sheathing secured to the outside of said posts, a side sill 45 comprising a rigid member secured to said posts on the outside thereof and an inwardly extending member for attachment to transverse floor supporting means, and means for securing said sheathing to the upper and lower portions of said 50 sill, the intermediate portion of said sill constituting a continuation of the outer surface of said sheathing.

8. For use in a railway car including a body framework including posts and transverse floor supports and sheathing members over the framework spaced vertically apart, a side sill for bridging the space between the adjacent edges of said sheathing members, said side sill having insets or rabbets extending longitudinally of the sill along its upper and lower edges on its outer side for receiving the adjacent edge portions of said sheathing members flush with the outer face of the side sill, and means for securing said side sill to said posts and to the transverse floor supports. 65

MARTIN P. BLOMBERG.
